UNITED STATES PATENT OFFICE.

FERDINAND G. UHLICH, OF ST. LOUIS, MISSOURI.

CASE FOR PHYSICIANS' PRESCRIPTION-PAPERS, &c.

SPECIFICATION forming part of Letters Patent No. 338,807, dated March 30, 1886.

Application filed January 18, 1886. Serial No. 189,026. (No model.)

To all whom it may concern:

Be it known that I, FERDINAND G. UHLICH, of the city of St. Louis, in the State of Missouri, have invented certain new and useful 5 Cases for Physicians' Prescription-Papers, &c., of which the following is a full, clear, and exact description, reference being had to the accompanying drawings, forming part of this specification, and in which—

10 Figure 1 is a perspective view of the case when open. Fig. 2 is a detail longitudinal section at 2 2, Fig. 1, but showing the lid closed and the marking-finger in its pocket.

This is a covered case, suitable in depth and 15 width to receive physicians' prescription-papers unfolded, and having a marking-finger movable to any part of the case, by which the place from which any prescription-paper is taken may be marked to enable its ready 20 turn to the same place.

The case may be made of any suitable material—such as mill-board, wood, or metal—and may be plain or ornamented in any manner. I have made the case of mill-board, covered 25 upon the outside with cloth and lined with paper.

A is the body of the case, and B a lid hinged thereto in any suitable manner. The lid may, if preferred, be made to fit on the box or 30 body in the manner of the lid of an ordinary pasteboard box.

C is a rod extending from end to end of the box, to give bearing to the marker D. The marker is bent in an eye at d, and through 35 this eye the rod C passes, the construction being such that the marker can be moved from end to end of the rod, and may be swung up or down at the free end upon the rod and eye as a hinge.

40 E is a transverse partition near one end of the box, forming a pocket, F, in which the marker may rest when not in use.

In Fig. 1 the marker is shown as indicating a space, G', between the prescription-papers G, from which a paper has been withdrawn for use, and to which it has to be returned.

H is a handle or loop by which the lid is opened.

The case, though being primarily intended 50 for the reception of physicians' prescription-papers, may be used for bills, receipts, and other similar purposes.

The ordinary manner of putting prescription-papers away is to stick them on a file- 55 wire. This has a number of disadvantages, among which may be mentioned that in looking up any paper the others have to be slipped along the wire backward and forward, which wears them away at the perforation, and is 60 liable to tear them at that point, and such manipulation is liable to render the writing indistinct or unreadable. To remove a paper, all that are above it must be removed from the file, which of course necessitates the work 65 of refiling. Then the writing on the papers is subjected more or less to the fading action of the light, and the papers themselves to dust, files, &c.

With the filing-case the papers are free, kept 70 straight and clean, and any one may be taken out without removal of any other.

I claim as my invention—

1. The combination, with the box, of a marker and a support therefor, said marker being 75 movable upon said support, substantially as set forth.

2. The combination of the box, the supporting-rod, and the marker engaging said rod and movable in a circular direction with 80 the rod for its axis, and also in the direction of the length of said rod, as set forth.

3. The combination, with the box, the marker, and a support upon which said marker slides, of a separate compartment or pocket 85 for the reception of said marker when not in use, as set forth.

FERDINAND G. UHLICH.
